UNITED STATES PATENT OFFICE.

WILLIAM C. HEDGCOCK, OF CHICAGO, ILLINOIS, ASSIGNOR TO AMERICAN STEEL
FOUNDRIES, OF CHICAGO, ILLINOIS, A CORPORATION OF NEW JERSEY.

REVERSIBLE FULCRUM-MEANS.

1,425,651.

Specification of Letters Patent. Patented Aug. 15, 1922.

Application filed August 8, 1921. Serial No. 490,500.

To all whom it may concern:

Be it known that I, WILLIAM C. HEDGCOCK, a citizen of the United States, residing at Chicago, in the county of Cook and State of Illinois, have invented certain new and useful Improvements in Reversible Fulcrum Means, of which the following is a specification.

This invention relates to a new and improved brake beam, for railway cars, and more particularly to a reversible fulcrum for such beams and to the connection between said reversible fulcrums and the compression member of the brake beam.

As is well known in the art, brake beams are required in two types, right hand and left hand, the difference between the types lying in the inclination of the fulcrum. Some brake beams are made with fulcrums freely rotatable about their axis, so that they may be changed from left hand to right hand.

Brake beams of that character are shown in my prior application, Serial No. 476,382, filed June 10th, 1921. The beam of this prior application comprises means for tightly connecting the fulcrum to the compression member, but contains no means for locking the fulcrum in either the right hand or left hand position.

It is an object of the present invention to provide new and improved means adapted to connect a reversible fulcrum to a brake beam compression member in such manner as to afford a tight connection and further to provide means for maintaining the fulcrum fixed in either its right hand or left hand position. It is an additional object to provide a device of this character which is simple in design and construction, and which is adapted to meet the various requirements for successful commercial uses. Other and further objects will appear as the description proceeds.

Broadly, my invention comprises a reversible fulcrum having a portion adapted to embrace the compression member of a brake beam, together with means for securing the fulcrum firmly connected to the compression member. In addition, means are provided for connecting the fulcrum and the securing means in such manner as to maintain the fulcrum in either its right hand or left hand position.

I have illustrated a preferred embodiment of my invention in the accompanying

drawings, in which Figure 1 is a top plan view of a trussed type of brake beam embodying my invention. Figure 2 is a fragmentary rear elevation of the same. Figure 3 is a view of Figure 2 as seen from above. Figure 4 is a view of Figure 2 as seen from the right, some parts being shown in section. Figure 5 is a top plan view of the securing member, and Figure 6 is a rear view of the securing member.

Referring now to the drawings; my invention is shown in connection with a trussed type of brake beam including a compression member 7, a tension member 8, heads 9 and the fulcrum 10. The fulcrum 10 is of the reversible type, and is provided with a banded portion 11 which embraces or surrounds the compression member 7. As best shown in Figure 4, the banded portion is provided with a lug 12 which engages an opening 13 in the compression member 7 to form a pivot about which the fulcrum may be rotated. As shown in Figure 2, the banded portion is provided with the angular walls 14 and 15, the walls 14 engaging the compression member when the fulcrum is in the right hand position, and the walls 15 engaging the compression member when the fulcrum is in the left hand position. The fulcrum is provided with the projection 16 which extends inwardly of the banded portion and engages the securing member 17. The edges of the extension 16 are somewhat beveled to engage the cam surface 18 of the securing member as the latter is moved in to place.

The securing member, as best shown in Figures 5 and 6, is provided with a wall 19 adapted to engage the side of the projection 16 when the end of the projection is seated on the flat surface 20. The member 17 is further provided with the tongue 21 adapted to be bent as shown in Figure 100 3 to retain the securing member in place relative to the projection. The securing member is also provided with the notched shoulders 22 which are adapted to overhang the projection. The projection 16 is provided with the intersecting transverse openings 22 and 23. These openings are adapted to selectively receive the cotter pin 24 when the fulcrum is in either the right hand or left hand position. This pin 24 further engages the notches in the shoulders 22 of the securing member 17.

The fulcrum 10 is provided with the fingers 25 adapted to engage the tension member 8. These fingers are so formed that the fulcrum may be rotated without the fingers interfering with the tension member 8.

In assembling my fulcrum with the compression member, the banded portion 11 is slipped over the compression member 10 until the lug 12 enters the opening 13. The securing member 17 is then inserted between the compression member and the extension 16, its cam surface 18 aiding this insertion and insuring rigid connection. 15 The tongue 21 is then bent up. The fulcrum may now be turned to either the right hand or left hand position, and the cotter pin inserted to maintain it in that position.

20 When it is desired to change the fulcrum from left hand to right hand or vice versa, the cotter pin is removed and replaced in the other opening after the fulcrum has been reversed. Obviously, the 25 cotter need not be used unless desired.

It is my intention to cover all modifications of the invention falling within the spirit and scope of the following claims:

I claim:

30 1. In a brake beam, the combination of a compression member, a reversible fulcrum having a portion embracing said compression member, means insertable between said compression member and fulcrum for securing the parts together and means co-acting with the securing means and the fulcrum to maintain the fulcrum fixed in an operative position.

40 2. In a brake beam, the combination of a compression member, a fulcrum having a portion embracing said compression member, means insertable between said compression member and fulcrum for securing the parts together and a removable member co-acting with the securing means and the fulcrum to maintain the fulcrum selectively fixed in either of two operative positions.

45 3. In a brake beam, the combination of a compression member, a reversible fulcrum having a portion embracing said compression member, means insertable between said compression member and fulcrum for securing the parts together, and a removable pin

engaging the securing means and passing through the fulcrum to maintain the fulcrum in operative position. 55

4. In a brake beam, the combination of a compression member, a fulcrum having a portion embracing said compression member, means insertable between said compression member and fulcrum for securing the parts together, and a removable pin engaging the securing means and passing through the fulcrum to maintain the fulcrum in operative position, the fulcrum being provided 60 with a plurality of passages for said pin corresponding to different operative positions of the fulcrum.

5. In a brake beam, the combination of a compression member, a fulcrum having a portion embracing said compression member and a projection extending toward said compression member, means insertable between the compression member and fulcrum for securing the parts together and a removable member engaging the securing means and the projection on the fulcrum for maintaining the fulcrum fixed in operative position. 70

6. In a brake beam, the combination of a compression member, a fulcrum having a portion embracing said compression member and a projection extending toward said compression member, means insertable between the compression member and fulcrum for securing the parts together and a removable pin engaging the securing means and passing through the projection on the fulcrum to maintain the fulcrum fixed in operative position. 85

7. In a brake beam, the combination of a compression member, a fulcrum having a portion embracing said compression member and a projection extending toward said compression member, means insertable between the compression member and fulcrum for securing the parts together, said securing means having notched shoulders overhanging the projection on the fulcrum and a removable pin engaging said notches and passing through the projection to maintain the fulcrum fixed in operative position. 95 100

Signed at Chicago, Illinois, this 2nd day of August, 1921.

WILLIAM C. HEDGCOCK.
